UNITED STATES PATENT OFFICE

150,042

DESIGN FOR A SMOKER'S PIPE STEM

John A. Warch, Woodlawn, Md., assignor of two-thirds to Ernest H. Warch and Herbert H. Hupfeldt, Baltimore, and Towson, Md.

Application June 13, 1946, Serial No. 130,670

Term of patent 14 years

(Cl. D85—8)

To all whom it may concern:

Be it known that I, John A. Warch, a citizen of the United States, residing at Woodlawn, in the county of Baltimore, State of Maryland, have invented a new, original, and ornamental Design for a Smoker's Pipe Stem, of which the following is a specification, reference being had to the accompanying drawings, forming part thereof.

Fig. 1 is a side view of a smoker's pipe stem showing my new design, and

Fig. 2 is an end view thereof as seen from the right of Fig. 1.

The opposite side presents a similar appearance as the side disclosed in Fig. 1.

I claim:

The ornamental design for a smoker's pipe stem, substantially as shown and described.

JOHN A. WARCH.
